Patented Sept. 30, 1975

236,938

FUNNEL FOR DIRECTING YARD DEBRIS INTO A BAG OR SIMILAR ARTICLE

Henry E. Bowen, Jr., 2637 Davis Ave.,
Carlsbad, Calif. 92008

Filed Oct. 9, 1974, Ser. No. 513,253

Term of patent 14 years

Int. Cl. D7—05

U.S. Cl. D7—189

FIG. 1

FIG. 2

FIG. 3

FIG. 4

FIG. 5

FIG. 6

FIG. 1 is a perspective view of a funnel for directing yard debris into a bag or similar article embodying my design.

FIG. 2 is a front view thereof.

FIG. 3 is a rear view thereof.

FIG. 4 is a top view thereof.

FIG. 5 is a side view thereof.

FIG. 6 is a bottom view thereof.

I claim:

The ornamental design for a funnel for directing yard debris into a bag or similar article, as shown.
